UNITED STATES PATENT OFFICE.

JOHN J. BURKE AND ARTHUR L. ADAMS, OF NEW YORK, N. Y.

MATRIX-HANDLING MEANS.

1,371,222.

Specification of Letters Patent. Patented Mar. 15, 1921.

Original application filed November 18, 1916, Serial No. 132,019. Divided and this application filed August 15, 1919. Serial No. 317,703.

To all whom it may concern:

Be it known that we, JOHN J. BURKE and ARTHUR L. ADAMS, citizens of the United States, and residents of the city, county, and State of New York, have invented certain new and useful Improvements in Matrix-Handling Means, of which the following is a specification.

Our invention relates to handling means intended primarily for apparatus for cleaning matrices, such as are used in a linotype machine, although our invention may be used for handling various other articles. As is known to those using linotype machines, the matrices frequently require cleaning to remove the foreign substances collected thereon during use in the linotype machine so as to permit the matrices to pass freely through the channels of the magazine and secure their perfect close alinement during the operation of casting.

This application is a division of our pending application, Serial No. 132,019, filed November 18, 1916, and entitled Matrix cleaning apparatus.

In the accompanying drawings, in which we have shown one embodiment of our cleaning apparatus.

Figure 1 is a side elevation;

Fig. 2 is a longitudinal sectional elevation on the line 2—2 of Fig. 4, looking in the direction of the arrow;

Fig. 3 is a detail cross-section, taken on the line 3—3 of Fig. 7, looking in the direction of the arrow;

Fig. 4 is a vertical cross-section, taken on the line 4—4 of Fig. 2, showing the top felt removed, and looking in the direction of the arrow.

Fig. 5 is an enlarged plan view of the right end of the machine shown in Fig. 1 with parts removed;

Fig. 6 is an enlarged vertical section of Fig. 5 with parts removed;

Fig. 7 is a detail plan view of the left side of the machine and the matrix-chute in section;

Fig. 8 is a detail elevation, taken on the line 8—8 of Fig. 7;

Fig. 9 is a top view, taken on the line 9—9 of Fig. 1;

Fig. 10 is a vertical cross-section, taken on the line 10—10 of Fig. 1;

Fig. 11 is a perspective view of the delivery receptacle; 55

Fig. 12 is a perspective view of the guide-weight in the delivery receptacle;

Fig. 13 is a latch-weight for the stacker or magazine; and

Fig. 14 is a perspective view of a matrix. 60

In the drawings, in which like numerals refer to like parts, 1 is a stand or framework supporting the apparatus, having loosely mounted in it shafts 2 and 3 carrying, respectively, gear-wheels 4 and 5. The 65 shaft 3 is connected by drum and belt or otherwise, with any suitable means for driving it, such as an electric motor, or other motive power (see Fig. 7). 6 is an endless chain or belt mounted on the gears 4 and 5 70 and rotating therewith. This endless chain or belt is provided with blocks 7 equally spaced thereon and carrying the spring-pressed pusher blocks 8 movably held in the blocks 7 by the pins 21—21 in the vertical slots shown in Fig. 6. The pusher block 8 is held normally in a raised position by the springs 22 located between it and the bottom of the cut-out portion of the block 7. 23 is a support or guide over which the 80 endless chain or belt 6 passes and by which it is kept from sagging, so as to maintain the pusher blocks 8 in operative contact with a matrix as it is being fed through the cleaning pads, as hereinafter set forth. 75

9 is a guide supported on the frame 1 attached to the support 10 by the bolt 11 and located in position so that as the chain 6 is operated the pusher 8 contacts with the guide 9 and is compressed against the 90 opposition of the springs 22 so that its upper surface will not project above the upper surface of the thinnest matrix which is to be cleaned. 85

Mounted on the frame 1 are cleaning-felt supports 13—13, holding the cleaning felts 12—12 (see Fig. 3) in position. Fixed in the frame 1 are posts 19—19 screw-threaded at their top carrying the screw-bolt 21. These posts 19 also carry yokes 18 and 25 100 for supporting the cleaning felts 14 and 16, the cleaning felt 14 being carried in cleaning frames 15 fixed to the yoke 25, and the cleaning felt 16 being attached to the block 17, which is attached to the yoke 18. 105 20, 20 are springs mounted on the posts

19 and located between the yokes 18 and 25 and the nuts 21^a so as to keep the yokes normally pressed downward to keep the felts in contact with the matrix to be cleaned. It will be noticed that in Fig. 3, a matrix 26 is shown between the felts showing how the felts clean the upper, lower and side surfaces of the matrix. These cleaning felts are arranged in sections. In the drawings, 10 we have shown them arranged in two sections with a space 26^a between them, the object of this arrangement being that the felts to the right of 26 are kept partially saturated with a cleaning fluid, while the 15 felts to the left of the passage 26^a are kept dry, so that the first set of felts on the right clean the matrix and the set of felts on the left dry the same.

20 A passage-way 8^a is arranged between the felts to permit passage of the pusher 8, as shown in Fig. 3.

In order that the saturated felts may be kept provided with a cleaning material, we have provided a cleaning-liquid reservoir 27 supported on the frame 1 by the supports 28. Leading from the reservoir 27 to a point above the felts are conduits 29, 29. Between the conduits and the reservoir there is a valve 30 (see Fig. 4) conical in shape, the movable member 31 of the valve being provided with little ducts or cavities adapted to receive a small quantity of the cleaning material, and then when the valve is operated, the movable member 31, of the valve provided with ducts or cavities, rotates so as to bring the ducts or cavities adjacent to the conduits 29, 29, whereby the cleaning liquid is fed down through the conduits 29, 29 and drops on to the cleaning felt so as to keep same saturated as desired. The movable member 31 of the valve is conically shaped, fits into a conical cavity in the valve body 30 and is held therein so as to make a tight joint by the spring 32 mounted on 40 the valve stem between the valve body 30 and the nuts 33. 34 is a removable cap to permit the receptacle 27 to be filled.

The valve 30 is operated as follows:

50 Fixed on the valve stem is a gear 35 which meshes with segment 36 fixed to the rocking arm 37 pivoted to the frame 1 by pivot 38, and normally held, as shown in Fig. 1, by the spring 39. Pivoted to the lower end of the rocking arm 37 by pivot 41 is an 55 arm 40, the opposite end of the arm 40 being in the form of a yoke, as shown in dotted lines in Fig. 1, so as to be supported on the shaft 2. This yoke-arm 40 is provided with a shaft 42 carrying a roller 43 loosely mounted thereon. Fixedly mounted on the shaft 2, so as to rotate therewith, is a block 44, having on its periphery a cam 45, which cam, coming in contact with the roller 43 on the yoke-arm 40, moves 60 same toward the left (see Fig. 1) against

the opposition of the spring 39, thereby rocking rocking-arm 37, moving segment 36 toward the right, rotating gear 35 fixed on the valve-stem, thereby operating the movable valve member 31 to feed the cleaning 70 fluid to the conduits 29, 29.

The matrices to be cleaned are placed in the magazine or stacker 46 mounted on rollers 47, which rollers are supported on tracks 48. The magazine or stacker 46 is also provided with rollers 49 held in operative engagement with the magazine or stacker 46 by roller-support 50. These rollers 49 are carried between rods or tracks 51, 51 held on the frame or foundation 1 by the support 80 10 (see Fig. 2).

As will be seen, the magazine or stacker 46 can be moved back and forth transversely to the machine, as shown in Figs. 1, 2, 4, 5 and 6. The magazine or stacker 46 is 85 provided with a cover 52, as shown in Fig. 4. The magazine or stacker 46 is provided with a series of compartments adapted to hold the matrices stacked one upon the other on their sides, as shown in Figs. 2, 4 90 and 5. These compartments are numbered, respectively, 53, 54 and 55.

When the desired number of matrices have been stacked in the magazine or stacker 46, a latch-weight 56 (see Fig. 13) is placed 95 on top of the stack of matrices. This weight is provided with a latch 57 supported in the frame 58 fixed to the weight 56 and held normally extended beyond the end of the weight, as shown in Fig. 13, by the 100 spring 59.

As the matrices are moved out from the bottom of the stack, as hereinafter described, the latch-weight 56 moves down the stacker a distance equal to the thickness of 105 the matrix which has been removed. When all of the matrices have been removed from a compartment in the stacker or magazine, the latch-weight 56 is at the bottom of the compartment, the latch 57 is brought adjacent to the opening or hole 58' in the back of the magazine compartment, and as it reaches that position the spring 59 pressing the latch 57 forces it through the opening 58' and into the position where it is adapted to engage with the reciprocating member 59' fixed on the rocking arm 60 so as to move the magazine or stacker 46 to bring the next compartment into operative relation, whereby the matrices may be fed from 120 the bottom of the compartment to and through the cleaning means, as hereinafter set forth.

It will be seen by reference to Figs. 2 and 6, that the guide 9 compresses the block 8 125 so that it engages only one matrix, but after the block is out from under the guide, the matrix above the one engaged or if there are no more matrices in the holder, then the weight 56, holds the block 8 down so 130

that it will not engage the upper edge of the opening in the plate 52 through which the matrices are discharged by the matrix-moving means.

5 This rocking-arm 60 is operated as follows:

The lower end of the rocking-arm 60 is pivoted by the pivot 61 to the support 62 attached to the frame 1. The rocking-arm is 10 provided with a pin 63 carrying a roller 64 (see Fig. 5) which operates in the cam-groove 65 located on the periphery of the block 44, so that as the block 44 rotates, the groove 65 moves the roller toward and away 15 from the frame-work, as shown in Fig. 4, thereby keeping the rocking arm 60 constantly moving back and forth so that whenever the latch 57 projects through the opening 58', the latch member 59' engages with 20 the latch and moves the magazine one compartment. The movement of the magazine or stacker 46 is arranged so that it will only be moved the distance required to bring the next compartment into line with the cleaning 25 mats. As the pusher-block 8 is brought around under the guide 9 and compressed, it contacts with the bottom matrix in a stack, moves it forward from the bottom of the stack and out between the cleaning felts, 30 as clearly shown in Fig. 6, until it becomes disengaged from the matrix at the end of the cleaning operation, and near the top of the delivery chute, as hereinafter set forth.

In order to prevent more than one matrix 35 from passing out of the stacker at a time, we have provided a spring-pressed stop 66 fastened to the door 52, of the stacker or magazine. As the matrix is moved out from the bottom of the stacker 40 it presses the spring-stop 66 out, and when the end of the matrix has passed and the pusher has passed, the spring-pressed stop 66 moves back to prevent the next matrix from moving out.

45 It is necessary in order that the matrix be easily replaced in the linotype machine that they be delivered on their feet, that is, the end of the matrix, shown to the right in Fig. 14. In cleaning, it is desirable that 50 they be fed through the cleaning device on their sides with the other end first. We have, therefore, provided means for delivering the matrices and stacking them in delivery receptacles on their feet so as to be convenient 55 for use. This delivery means we will now describe.

At the end of the dry-cleaning felts, as shown in Figs. 2 and 8, we have arranged a chute 67, in the bottom of which is an opening 68 corresponding in shape and form to a matrix. On the lower side of this opening is a small shelf 69 arranged at the end of the chute, so that as the matrix passes down the chute 67, it passes across the open-

ing until the top of the matrix strikes the 65 end of the chute and rests on the shelf 69 and when the feet of the matrix have come adjacent to the upper end of the opening 68, it falls by gravity, as shown in Fig. 8, and the matrix is carried down to the bottom of the delivery chute feet first.

At the bottom of the chute 67 is a star-wheel 70 loosely mounted on the shaft 71 (see Fig. 9). This shaft 71 is loosely mounted in the frame-work 1 and is screw-threaded at one end to engage with the screw-nut 72. Located between the screw-nut 72 and the frame 1 is a spring 73. 74 is a block keyed to the shaft 71 by key 75. Loosely mounted on the shaft 71 is a 80 sprocket 76 adapted to engage with the belt 77 operated by a sprocket fixed to the driven shaft 3 of the apparatus. 78 is a suitable leather or friction washer, so arranged that the star-wheel 70 is rotated by 85 the rotation of the gear 76, the rotation of which is transmitted to the star-wheel 70 by the friction washer 78. The friction between the gear 76 and the star-wheel 70 is regulated by operation of the nut 72 which 90 draws the shaft 71 outward and creates a stronger spring tension between the star-wheel 70, gear 76 and the friction washer 78, whereby the star-wheel is rotated.

80 is a delivery receptacle provided with 95 shelves 81, 81, 81. This delivery receptacle 80 is movably supported on the frame 1 by the support 82 fastened to the frame 1 and carrying the vertical supports 83 engaging with the tracks 84, 84. At the bottom of the 100 delivery receptacle 80 is an arm 85 carrying pins 86, 86 supporting a sliding door 87, the bottom of the door being held against downward motion by the support 88. Located on the outside of the delivery receptacle 80 and bolted to the casing thereof, are spring-stops 89 adapted to engage with stop-arm 90 secured to the support 82. These stops 89 are provided with pins 91 which pass through openings at the back of each compartment in the delivery receptacle. 110

For each compartment of the delivery receptacle we provide guide-weights 92, shown in Fig. 12, having a projection 93 adapted to engage and freely slide in the groove or guide-way 94 in each of the shelves 81, 81, 81. These guide-weights are held in place by plate 93' screwed to the underside thereof so as to hold the guide-weights in operative relation to the shelves 81, 81, 81. When the delivery receptacle 115 is placed in the machine, these guide-weights are to the left of the shelves.

As the matrices pass down through the chute 67, reversing their direction of movement so as to land on their feet, the star-wheel 70, rotating, moves the weight 92 back a distance equal to the thickness of the 120 125

matrix, as shown in Fig. 2, until the weight has reached a point where it engages with the pin 91, and as the next matrix is put on the delivery receptacle shelf and packed by the star-wheel, the pin 91 is moved out and moves the stop 89 out of engagement with the stop-arm 90 so as to permit the delivery receptacle to drop until the stop-arm 90 engages with the next stop-pin 89, 10 which brings the next shelf into operative relation to the star-wheel and the delivery chute.

As the delivery receptacle drops, the door 87 remaining stationary, the lower shelf, 15 as shown in Fig. 11, is brought down a distance equal to the height of the shelf, and as it does so, the shelf passes down so that the door 87 closes the end thereof to keep the matrices in position.

20 The operation of our cleaning apparatus is as follows:

The magazine or stacker 46 having been filled with matrices and placed in position on the machine, power is supplied and the 25 shaft 3 rotates, thereby rotating shaft 2 through the medium of the sprocket wheels 5 and 4 and also rotates shaft 71 through the endless belt 77. A pusher 8 is brought around under the guide 9, engages with the 30 end of a matrix in the bottom of the stack, moves the same out from under the stack, raising the stop 66 until it has cleared the stack, when the weight-latch 56 moves the stack down a distance equal to the thickness 35 of the matrix removed and the stop 66 returns to normal position, preventing any other matrices from passing out. The matrix which has just been removed is passed between the cleaning felts 12, 14 and 16, first 40 being cleaned by the first set of moist felts, and then dried by the second set of felts, after which it is carried to the delivery chute where the pusher 8 becomes disengaged from it and the matrix, by gravity, 45 passes down the delivery chute 67, the forward end passing over the opening and striking against the end of the chute as it rests on the shelf 69, when the feet of the matrix pass down through the far or up- 50 per end of the opening, as shown in Fig. 8, and by gravity, the matrix reaches the bottom, where it engages with the star-wheel 70. The star-wheel 70, rotating, presses the matrix forward until the lowest shelf of the 55 delivery receptacle 80 has been filled, when the weight 92, engaging the pin 91, presses the pin out, releases the stop 89 from engagement with the stop-arm 90 and permits the delivery receptacle to move downward 60 one shelf, until the stop 89 on the next above shelf, engages with the stop-arm 90 to stop further movement downward of the delivery receptacle.

As the delivery receptacle moves down-

ward, the lower shelf passes in front of the 65 door 87 and the matrices are held in position ready for use when the delivery receptacle is removed from the apparatus.

When all of the matrices in the first compartment of the magazine or stacker 46 are 70 removed, the weight 56, having reached the bottom of the compartment, the latch 57 passes through the opening 58', engages with the latch member 59'. The rocking-arm 60 moves the magazine to the right of 75 the apparatus, as shown in Fig. 4, a distance so as to bring the next compartment into operative relation with the cleaning felts. While this is being done, the rotation of the shaft 2 operates yoke-arm 40 through cam 80 45, roller 43, to rock rocking-arm 37 against opposition of the spring 39, thereby moving segment 36 to rotate gear 35 so as to revolve the valve stem and feed a given quantity of cleaning liquid to the cleaning felts. 85

Of course, modifications and changes can readily be made by any one skilled in the art without departing from the spirit of our invention.

Having described our invention, what we 90 claim as new and desire to secure by Letters Patent is:

1. In a device of the class described, the combination of means for holding matrices, means for feeding said matrices from said holding means, said holding means carrying a plurality of stacks of matrices and means for moving said holding means to bring different stacks of matrices into operative relation to said feeding means. 95

2. In a device of the class described, the combination of means adapted to hold articles arranged in a plurality of stacks, means for moving the articles from a stack and means the operation of which is dependent 105 upon the height of a stack for moving said holding means to bring said stacks into operative relation with said moving means.

3. In a device of the class described, the combination of means adapted to hold matrices arranged in a plurality of stacks, means for removing the matrices from a stack and means for successively bringing said stacks into coöperative relation with said last-named means. 110

4. In a device of the class described, the combination of means adapted to hold articles arranged in a plurality of stacks and means for automatically moving all of the articles, one at a time, from all of said 120 stacks.

5. In a device of the class described, the combination of means adapted to hold matrices arranged in stacks, means for moving the matrices from a stack in said holding means and means for effecting a relative movement between said matrix-holding means and said matrix moving means to 125

- bring the various stacks and the matrix moving means into operative relation to each other.
6. In a device of the class described, the combination of a stacker adapted to hold matrices in stacks, means for moving said stacker and means carried by said stacker and normally disengaged from said moving means but adapted to engage with said moving means to effect the movement of the stacker when a stack is depleted.
7. In a device of the class described, the combination of a stacker adapted to hold articles in stacks, means for effecting the moving of said stacks and means for effecting the operation of said moving means when one of said stacks is depleted.
8. In a device of the class described, the combination of a stacker adapted to hold articles in stacks, means for effecting the moving of said stacker and means carried by one of said stacks in said stacker for controlling said moving means.
9. In a device of the class described, the combination of a holder adapted to hold matrices in stacks, means for moving the matrices relatively to said stacks, means constantly actuated by said last-mentioned means for moving said holder to bring different stacks into operative relation with said matrix-moving means and means dependent upon the height of the stack for rendering operative said holder-moving means.
10. In a device of the class described, the combination of a holder adapted to hold articles in stacks, means for moving the articles relatively to said stacks, said holder being movable to bring different portions thereof to substantially the same position, constantly acting means for moving said holder and means automatically set into operation when a stack is depleted for rendering operative said last-named means.
11. In a device of the class described, the combination of a holder adapted to hold matrices in stacks, means for moving matrices relatively to said stacks, said holder being movable to bring different portions thereof to substantially the same position and means comprising a controlling member movable by gravity with the height of a stack to cause movement of said holder to bring different portions of said holder to substantially the same position.
12. In a device of the class described, the combination of a holder adapted to hold matrices in stacks, means for moving matrices relatively to said stacks and means for moving said holder to bring different portions of said holder in substantially the same position when a stack is depleted.
13. In apparatus of the class described, a matrix-holder, means engaging the feet of said matrices for moving them while resting 65 on their sides from said holder, a matrix storing means and means for delivering said matrices into said storing means on their feet.
14. In an apparatus of the character described, matrix-moving means engaging the feet of the matrices for moving them while they are resting on their sides and a delivery chute leading from said means, said delivery chute provided with means for delivering 75 said matrices on their feet.
15. In a device of the class described, the combination of means engaging the feet of matrices for moving them while they are resting on their sides, storing means for said 80 matrices and means receiving said matrices from said moving means and delivering them to said storing means upon their feet.
16. In a device of the class described, the combination of article-moving means engaging the foot of the article for moving it while it is resting on its side and means for receiving the matrix therefrom and delivering it upon its feet.
17. In an apparatus of the character described, matrix-moving means, a matrix-stacker arranged to be brought into operative relation to said moving means and means for automatically moving said stacker when all of the matrices in a single 95 stack have been removed therefrom.
18. In an apparatus of the character described, feeding means adapted to feed matrices, said feeding means being provided with a spring-pressed member, and a guide 100 so arranged that said feeding means will feed one matrix at a time.
19. In an apparatus of the character described, matrix-holding means adapted to hold matrices arranged in stacks, said means being adapted to be moved so as to bring the different stacks into substantially the same position, means for supporting said holding means and means for moving said holding means so arranged as to move said holding 105 means when all the matrices in a stack have been removed.
20. In an apparatus of the character described, matrix-holding means adapted to simultaneously hold a plurality of stacks of 110 matrices and movable to bring each stack to substantially the same position, means for feeding the matrices from said holding means so arranged that only one matrix will pass from the holding means at a time.
21. In a device of the class described, the combination of a member having an opening for the passage of an article, a holder adapted to simultaneously carry a plurality of stacks of the articles and movable to bring 115 said stacks opposite said opening and means for feeding said articles from said holder through said opening.

22. In a device of the class described, the combination of a member having an opening for the passage of matrices, a holder adapted to simultaneously carry a plurality of 5 stacks of matrices and movable to bring said stacks opposite said opening at different times to permit matrices from said holder to be discharged through said opening and means for feeding said matrices 10 from said holder through said opening a predetermined number at a time.

23. In a device of the class described, the combination of a member having an opening for the passage of matrices, a holder 15 adapted to simultaneously carry a plurality of stacks of matrices and movable to bring said stacks opposite said opening at different times to permit matrices from said holder to be discharged through said opening, means for feeding said matrices from 20 said holder through said opening and means associated with said opening to control the number of matrices passing through said opening at one time.

24. In a device of the class described, the combination of a member having an opening for the passage of matrices, a holder adapted to simultaneously carry a plurality of stacks of matrices and movable to bring 30 said stacks opposite said opening at different times to permit matrices from said holder to be discharged through said opening, means for feeding said matrices from said holder through said opening and means 35 operated from said feeding means for moving said holder.

25. In a device of the class described, the combination of a member having an opening for the passage of matrices, a holder 40 adapted to simultaneously carry a plurality of stacks of matrices and movable to bring said stacks opposite said opening at differ-

ent times to permit matrices from said holder to be discharged through said opening and means for feeding said matrices 45 from said holder through said opening, said holder being provided with a guide.

26. In a device of the class described, the combination of a member having an opening for the passage of matrices, a holder 50 adapted to simultaneously carry a plurality of stacks of matrices and movable to bring said stacks opposite said opening at different times to permit matrices from said holder to be discharged through said opening, means for feeding said matrices from 55 said holder through said opening and a guide opposite said opening for guiding said matrix feeding means.

27. In a device of the class described, the 60 combination of a member having an opening for the passage of matrices, a holder adapted to carry a plurality of stacks of matrices and movable to bring said stacks opposite said opening, means for feeding 65 said matrices through said opening and including a spring-pressed member and a member movable upon a change of length of a stack and co-operating with said spring-pressed member to prevent it from engaging 70 said first-named member.

28. In a device of the class described, the combination of a holder for a stack of matrices, means for moving matrices from the stack, a member having an opening through 75 which said matrices are moved by said moving means and means brought into operative position upon change of length of the stack to prevent said moving means from engaging said member.

In testimony whereof, we have signed our names to this specification.

JOHN J. BURKE.
ARTHUR L. ADAMS.

It is hereby certified that in Letters Patent No. 1,371,222, granted March 15, 1921, upon the application of John J. Burke and Arthur L. Adams, of New York, N. Y., for an improvement in "Matrix-Handling Means," errors appear in the printed specification requiring correction as follows: Page 5, line 52, claim 11, before the word "height" insert the word *changing*; same page, line 88, claim 16, for the word "matrix" read *article*; and that the said Letters Patent should be read with these corrections therein that the same may conform to the record of the case in the Patent Office.

Signed and sealed this 26th day of April, A. D., 1921.

[SEAL.]

T. E. ROBERTSON,

Commissioner of Patents.

Cl. 193—24.
